UNITED STATES PATENT OFFICE

2,396,876

FLUE CAP

Olaf L. Olsen, Petersburg, Territory of Alaska

Application October 2, 1944, Serial No. 556,807

1 Claim. (Cl. 98—73)

This invention relates to a flue cap, or smoke stack or chimney protector or cover.

A primary object of this invention is the provision of an improved flue cap or cover for chimneys or the like adapted to reduce to a minimum the possibility of ingress of wind or the like into chimney.

A still further object is the provision of such a device adapted to be tilted in the direction the wind is blowing, in order to protect the fire from blowing out, with the resultant inconvenience and danger attendant upon possible explosion in the stove or furnace associated with the flue.

Still another object is the provision of such a device which will be sturdy and durable in construction, reliable and efficient in operation, and relatively simple and inexpensive to manufacture.

Other objects will in part be obvious and in part pointed out as the description of the invention proceeds and partly shown in the accompanying drawings, wherein there is disclosed the preferred embodiment of this inventive concept.

In the drawings:

Figure 1 is a side elevational view of one form of device embodying this invention, certain hidden parts being indicated in dotted lines.

Figure 2 is an end elevational view of the device shown in Figure 1.

Figure 3 is a top plan view of the device.

Figure 4 is a sectional view taken substantially along the line 4—4 of Figure 2, and

Figure 5 is a sectional view taken substantially along the line 5—5 of Figure 1.

Like reference numerals refer to like parts throughout the several views of the drawings.

In the drawings there is generally shown at 10 a cylindrical sleeve, adapted to be positioned over the end of a chimney, stack or flue 11. Mounted on the upper portion of sleeve 10 is an oblate flange 12, having a centrally disposed aperture therein of a dimension substantially equal to the diameter of the chimney, and being secured to the sleeve 10 as by rivets.

Secured to sleeve 11 and longitudinally aligned with the flange 12 is a hood 14, the upper portion of which is spaced above the top of the sleeve, and the securing means taking the form

of a bolt 15 threaded at both its extremities, and secured in position, in pivotal association with the sleeve 10, as by nuts 16.

Secured to the sides of hood 14, as by rivets 17 or the like, are two extending wings 18.

From the foregoing the method of operation of the device should now be readily understandable. It will be readily seen that when the device is rotated in the direction of blowing wind, the action of such wind upon the protruding wings 18 will tilt the device about a pivot comprised of the bolt 15 until the extremity or edge of the member 14 is tilted into contact with the flange or plate 12. This will effect the closure, of the chimney opening on the side thereof adjacent the direction of the oncoming wind. Such closure will remain in effect until the pressure of the wind is diminished, or its direction shifted at which time the parts will resume a balanced position shown in Figures 1 and 2. As the wind resumes in intensity or changes in direction the device will again be closed until such time as the velocity is again diminished.

From the foregoing it will now be seen that 25 there is herein provided a device accomplishing all the objects of this invention and others including many advantages of great practical utility and commercial importance.

As many embodiments may be made of this 30 inventive concept, and as many modifications may be made in the embodiment hereinbefore shown and described, it is to be understood that all matter herein is to be interpreted merely as illustrative and not in a limiting sense.

35 I claim:

In a flue cap or the like, the combination of a sleeve adapted to be positioned around a flue, an oblate plate secured to said sleeve and having a centrally disposed aperture adjacent the top of the sleeve, a hood pivotally secured to said sleeve at a point below said plate extending over the top of the flue, and wings on said hood extending below said plate, the ends of said plate extending a substantial distance beyond the extremities of said hood to limit the pivotal movement thereof, the pressure of wind on said wings serving to tilt said hood into engagement with said plate.

OLAF L. OLSEN.
